UNITED STATES PATENT OFFICE.

JOSEPH LINDBURG, OF BAY RIDGE, BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed February 23, 1924. Serial No. 694,548.

To all whom it may concern:

Be it known that I, JOSEPH LINDBURG, a citizen of the United States, residing in Bay Ridge, Brooklyn, in the county of Kings, city and State of New York, have invented certain new and useful Improvements in Typewriting Machines, of which the following is a specification.

This invention relates to card-guiding and card-gaging means for the revoluble platens of front-strike typewriting machines, and embodies improvements over the structure shown in the patent to Helmond, No. 1,302,161, in which the wing-scale and card-guide are shiftable up and down with the platen, being for that purpose mounted upon arms which are connected to the platen-shift-rail, and which are also confined by spring-fingers secured upon the fixed type-bar segment and having rolls to run upon the wing-scale.

It is an object of the present invention to enable the machine to control stiff cards. These cards have to bend in passing around the platen which places them under stress, causing them to tend to straighten out and to bulge forward at the middle, away from the platen. This bulging occurs in the very portion of a card where the types must strike, and where therefore the card needs to be supported or backed in order to receive the impression.

This trouble is overcome by locating the scale-pressing rolls in direct engagement with the scale relatively close to the printing point, where they press the thin metal scale and guide toward the platen without flexing, and thus overcome the tendency of the middle portion of the card to bulge away from the platen.

The rolls bear upon the wing-scale at points close to upwardly-extending guiding horns, which are made in the form of projections rising from the upper edge of the wing-scale, one at each side of the printing point. The horns are each of tapering form with edges flaring away from the platen so as to stiffen the horn and also reduce the extent of rubbing contact with the stiff card which is bent around the platen.

The wing-scale is supported at its lower edge to the front of the platen and is inclined to the rear in such a way that the

upper graduated edge lies closely adjacent the platen, while the body of the wing-scale 55 clears the platen so as to avoid contact with the work. Since the wing-scale rises vertically with the case-shift frame of the machine, it is important that the spring-pressed rolls, which bear against the wing-scale, engage vertical surfaces, for otherwise the pressure of the rolls against the wing-scale and of the wing-scale against the platen would be varied by the case-shifting movement of the scale. Such case-shifting 60 movement, moreover, would be opposed in one direction by the pressure of the rolls. Tapering bosses are accordingly pressed forward from the body of the wing-scale to provide vertical bearing surfaces for the 70 pressure-rolls.

The direct bearing of the rolls against the scale is advantageous not only for controlling the cards, but also because of the accuracy and simplicity with which the letter-space position of the wing-scale relative to the printing point can be obtained and preserved. The letter-space position of the wing-scale is controlled by peripheral flanges on the scale-pressing rolls, which are 75 arranged to ride in vertical slots in the bosses of the wing-scale. The elimination of a train of connections between these rolls and the wing-scale conduces very materially to the accuracy and permanence of the 80 wing-scale adjustment.

Other features and advantages will hereinafter appear.

In the accompanying drawings,

Figure 1 is a front elevation of a front-strike Underwood typewriting machine with the present improvements applied thereto.

Figure 2 is a sectional side elevation at about the line 2-2 of Figure 1.

Figure 3 is a sectional side elevation 95 through the wing-scale, taken at about the line 3-3 of Figure 1.

Figure 4 is a front elevation of a fragment of the wing-scale.

Figure 5 is a horizontal section through 100 one of the horns, at the line 5-5 of Figure 4.

In said Underwood machine type-bars 10 swing their types to strike rearwardly 105 against a platen 11 which is mounted upon a frame 12 that is shifted up and down by

means of a rail 13. This rail is mounted upon a swing-frame 14 operated by a key-lever 15. The type-bars are mounted in a segment 16.

5 In front of the platen extends a wing-scale 17 which remains stationary while the platen moves endwise but which shifts up and down with the platen. Said wing-scale, by means of pendent ears 18 and screws 19, 10 is connected to a horizontal bar 20 extending along the segment and bent at its ends to form a pair of arms 21, which, at their lower ends, extend rearwardly under the rail 13 and are pivoted at 22 to the shift-rail 15 frame 14 and held to the frame 14 by springs 23.

Midway of its ends the scale has a type-opening 24, and close to said type-opening are mounted rolls 25 for the wing-scale, said 20 rolls mounted upon the upper ends of spring-fingers 26, which are attached to the front face of the segment 16 by screws 27 which are threaded into holes usually provided in the segment; the improvement being readily applicable to existing machines.

The middle of the wing-scale has bosses 28 pressed forwardly from its body to bear the pressure of the rolls 25; these bosses being vertically slotted at 29 to receive peripheral 30 flanges 30 formed on the rolls 25 to fit in said slots and prevent relative endwise play between the rolls and the wing-scale 17. The rolls thus run upon the wing-scale at the borders of the slots 29.

35 It will be noted that the wing-scale 17 is supported at its lower end somewhat in advance of the front of the platen 11 and is inclined toward the rear to locate its upper scale-bearing edge in proximity to the platen 40 while maintaining its body clear of the platen to avoid obstruction of the work. Since the wing-scale rises vertically in its case-shifting movement, however, it is important that the rolls 25 bear against vertical surfaces, since otherwise they would cause the pressure of horns 31 against the platen to be varied by the case-shifting movement. The bosses 28 are accordingly formed to taper from top to bottom, as best 50 shown in Figures 2 and 3, so that the roller-engaging surfaces of the bosses are caused to extend vertically.

The direct engagement of the rolls 25 with the wing-scale is also advantageous, because 55 it eliminates the provision of a train of connections between these elements, all of which would be factors in determining the final adjusted position of the wing-scale with relation to the printing point.

60 Said rolls bear upon the scale at points close to the pair of horns 31 projecting upwardly from the wing-scale close to the printing point, which is marked X, and curving rearwardly and bearing at their tips 65 against the platen 11. The horns are flared

laterally at 32 away from the platen to guide the approaching cards under themselves, and are also flared at their tips at 33 away from the platen to minimize the area of the stationary horn bearing against the card.

70 The card may be clipped by its front edge in a card-holder 34 of the usual type, extending around the platen and fixed thereto. A card-holder of this type is disclosed in the patent to Joerissen, No. 858,655, granted July 2, 1907.

75 It is an important point that the spring-fingers 26 are made very stiff, and that they are not under stress when there is no work in the machine. The horns are not, therefore, required to press against the work when the machine is being used, for example, for correspondence work, but may be so arranged that they are normally located at a short distance from the platen. This is an 80 important point since it obviates the smearing of the duplicate sheets by their carbons, which would result if the horns were supported against the pressure of the spring-fingers 26 by work of this character.

85 Variations may be resorted to within the scope of the invention, and portions of the improvements may be used without others.

90 Having thus described my invention, I claim:

95 1. In a typewriting machine, the combination with a revoluble up-and-down shiftable platen and writing instrumentalities, of a thin, broad card-guide plate supported 100 at the front of the platen and extending therewith and mounted to shift up and down therewith and having a type-clearing recess, and means mounted upon the stationary framework and directly pressing against the card-guide on opposite sides of the 105 weakened portion formed by the type-clearing recess and close to the printing point, whereby said shifting card-guide is at all times supported against bowing outward at the weakened portion, and the card consequently held firmly against said platen at the printing point in all positions of the 110 platen.

115 2. In a typewriting machine, the combination with a case-shiftable frame, a revoluble platen therein and writing instrumentalities, of an integral combined rising wing-scale and card-guide supported to the 120 front of the platen and inclined rearwardly to locate its scale-bearing upper edge in proximity to the platen at the line of writing, and presser-rolls to bear directly against the combined wing-scale and card-guide to press the card-guiding portion thereof 125 against the platen, the combined wing-scale and card-guide having bosses pressed forwardly from it which taper from top to bottom, to provide vertical walls for engagement with the presser-rolls, so that the pressure of the combined wing-scale and 130

card-guide is caused to remain uniform in its upper and lower case-positions and in its movement between said positions.

3. In a typewriting machine, the combination with a case-shiftable frame, a revoluble platen therein and writing instrumentalities, comprising a type-segment, of a rising wing-scale shiftable between lower and upper case-positions with the platen, 10 said wing-scale having letter-space graduations along its upper edge and having vertical slots at accurately determined locations, and means for obtaining and preserving an exact letter-space location of the wing-scale 15 graduations relatively to the printing point, comprising rolls mounted in predetermined relation to the printing point on the type-segment, and having flanges snugly fitting in the slots of the wing-scale to ride therein 20 when the wing-scale is shifted between its upper and lower case-positions.

4. In a typewriting machine, the combination with a traveling carriage, a revoluble platen mounted therein and writing instrumentalities, of a combined scale and card-guide consisting of a thin piece of sheet-metal having card-pressing horns projecting upward and rearward at opposite sides of the printing point to press the work against 25 the platen, said horns being tapered and being bent forward along their tapered edges to increase their rigidity and reduce the area 30 of rubbing contact with a card in the machine as it travels from side to side with the platen, and means to engage the scale in 35 proximity to the horns to press the horns firmly toward the platen.

5. In a typewriting machine, the combination with a traveling carriage, a revoluble platen mounted therein with provision 40 for vertical case-shifting movement, and writing instrumentalities, of a rising scale and card-guide mounted for case-shifting movement in unison with the platen, con-

sisting of a thin piece of sheet-metal having 45 card-pressing horns projecting upward at opposite sides of the printing point to press a card against the platen, said horns being tapered and bent forward along their tapered edges to increase their rigidity, and 50 bosses pressed forward from the body of the scale and guide to stiffen the latter and to provide vertical guiding surfaces for controlling the case-shifting movements of the scale and guide, and means to engage said 55 guiding surfaces and press the scale and guide toward the platen.

6. In a typewriting machine, the combination with a case-shiftable revoluble platen and writing instrumentalities, of a combined rising scale and work-guide, and means to press the rising scale toward the platen in either upper-case or lower-case position, the rising scale including means to bear upon the platen to press the work thereagainst and being formed with bearing members which are directly engaged by the rising scale-pressing means, said bearing members having vertical bearing surfaces to cause the pressure exerted against the work to be constant.

7. In a typewriting machine, the combination with a revoluble platen, of a relatively thin letter-space and aligning scale movable adjacent the front of the platen, said scale having a type-clearing recess and including work-engaging fingers extending upward adjacent both sides thereof, and means for applying pressure to the scale at opposite sides of the weakened portion formed by the type-clearing recess, substantially beneath the fingers and close to the printing point, whereby the scale is supported against bowing outward at the weakened portion, and the fingers consequently held in firm engagement with the platen.

JOSEPH LINDBURG.
